LADY'S PEN OR THE LIKE

James A. Engelmann, Highland Park, Ill., assignor to Paper Mate Manufacturing Company, Culver City,
Calif., a corporation of Delaware

Application November 30, 1956, Serial No. 44,009

Term of patent 14 years

(Cl. D74—17)

Fig. 1.

Fig. 2.

Fig. 3.

Fig. 4.

Fig. 1 is a front elevational view of a lady's pen showing my new design;

Fig. 2 is a side elevational view thereof;

Fig. 3 is a rear elevational view thereof; and

Fig. 4 is a top plan view thereof.

My new design is characterized by the presence of the graduated jewels on the push button arranged as shown.

The essential features of my design reside in the portions shown in solid lines on the drawing.

I claim:

The ornamental design for a lady's pen or the like, substantially as shown and described.
